HOLDER FOR A CIGARETTE LIGHTER

Willard C. Knight, 2822 Cambridge Blvd.,
Fort Wayne, Ind. 46808

Filed Mar. 2, 1966, Ser. No. 1,246

Term of patent 7 years

(Cl. D87—5)

FIG. 1 is a front elevational view of a holder for a cigarette lighter showing my new design;

FIG. 2 is a rear view thereof;

FIG. 3 is a side view thereof;

FIG. 4 is a bottom view; and

FIG. 5 is a perspective view.

I claim:

The ornamental design for a holder for a cigarette lighter, as shown.
